UNITED STATES PATENT OFFICE.

SAMUEL A. BISHOP, OF SMETHPORT, PENNSYLVANIA.

MACHINE FOR SMOOTHING AND POLISHING FLOORS.

SPECIFICATION forming part of Letters Patent No. 664,232, dated December 18, 1900.

Application filed May 18, 1900. Serial No. 17,160. (No model.)

To all whom it may concern:

Be it known that I, SAMUEL A. BISHOP, a citizen of the United States, residing at Smethport, in the county of McKean and State of Pennsylvania, have invented a new and useful Machine for Smoothing and Polishing Floors, of which the following is a specification.

The invention relates to improvements in machines for smoothing and polishing floors. 10 The object of the present invention is to improve the construction of machines for smoothing and polishing floors and to provide a simple and comparatively inexpensive one adapted to be operated by pushing it along 15 the floor or other surface to be operated on and capable of permitting the grinding and polishing disk or wheel to continue its rotation after the operating mechanism or gearing has ceased to move, whereby the machine 20 may be caused to operate for considerable time over a particular spot or place of the floor or other surface after the driving and polishing wheel has attained a considerable speed.

The invention consists in the construction 25 and novel combination and arrangement of parts, hereinafter fully described, illustrated in the accompanying drawings, and pointed out in the claims hereto appended.

In the drawings, Figure 1 is a plan view 30 of a smoothing and polishing machine constructed in accordance with this invention. Fig. 2 is a side elevation of the same. Fig. 3 is a transverse sectional view. Fig. 4 is a detail view illustrating the construction of the 35 clutch. Fig. 5 is a detail view of the pinion which forms the lower member of the clutch. Fig. 6 is a reverse plan view of the upper section of the clutch.

Like numerals of reference designate corresponding parts in all the figures of the drawings.

1 designates a supporting-frame provided at opposite sides of its rear portion with bearings 2 for the reception of an axle 3, to the 45 ends of which are fixed carrying-wheels 4, which support the rear portion of the machine. The axle 3 has keyed or otherwise fixed to it a vertical gear-wheel 5, which meshes with a horizontal pinion 6, located at 50 the lower end of a rear vertical shaft 7 and connected with the same by a clutch to permit the shaft 7 to continue its rotation after

the axle has stopped by reason of stopping the machine. The clutch, which may be constructed in any suitable manner, preferably 55 consists of an upper clutch member or collar 8, the said pinion 6, and a series of balls 9, interposed between the collar and the pinion and arranged in recesses or sockets 10 of the collar and adapted to operate in grooves 11 60 of the pinion. The grooves 11 of the pinion have inclined bottom walls extending from the upper surface or face of the pinion to shoulders 12, against which the balls abut when the pinion is rotated forwardly by the 65 axle 3. When the machine is stopped, or rather when its forward movement has ceased, the shaft 7 continues its rotation and the balls are carried forward by the collar or upper clutch member 8, the inclined portions of the 70 bottoms of the grooves permitting such forward movement of the balls and lifting the same into the upwardly-extending recesses or sockets of the lower face of the collar or clutch member 8 as the same rotates. The 75 collar, which may be secured to the rear shaft 7 in any suitable manner, is preferably provided with a hub or sleeve 13, having threaded perforations for the reception of clamping screws 14, which engage the shaft 7. 80

The shaft 7 is journaled in upper and lower bearings 15 and 16 of the rear portion of the supporting-frame, in line with its center thereof, and it carries a rear horizontal gear-wheel 17, located above the supporting-frame 85 and meshing with a horizontal pinion 18 of an intermediate vertical shaft 19, which is journaled in upper and lower bearings 20 and 21 of the upper portion of the frame. The lower bearings are mounted upon a horizontal 90 supporting bar or piece 22, which is located above the carrying-wheels and which is secured to the front and rear portions of the frame, as clearly illustrated in Fig. 2 of the accompanying drawings. The intermediate 95 shaft 19 carries a front horizontal gear-wheel 23, located below the plane of the rear horizontal gear-wheel 17 and meshing with a horizontal pinion 24 of a front vertical shaft 25, located at one corner of the supporting-frame 100 in advance of the adjacent carrying-wheel and journaled in upper and lower bearings 26 and 27. The lower end of the vertical shaft 25 has secured to it a grinding and polishing

disk or wheel 28, designed to be constructed of any suitable material to suit the character of the surface to be operated on and the work to be performed, and it is held against such surface by the weight of the front portion of the machine. When the machine is moved forward, the axle is rotated and through the gearing, heretofore described, communicates motion to the vertical front shaft and rotates the grinding and polishing wheel or disk. The frame is provided with a rearwardly-extending inclined handle 28, having a suitable grip or handle-bar 29, adapted to be grasped by the operator, and the machine may be readily tilted to lift the grinding and polishing wheel from the supporting-surface in transporting the machine from one place to another and when it is desired that the grinding and polishing wheel attain a comparatively high rate of speed before bringing it into contact with the surface to be operated on. It will also be apparent that the pressure of the grinding and polishing wheel upon the surface to be dressed may be readily regulated by the operator from the rear of the machine by pressing down upon the handle to counterbalance the weight of the machine to a greater or less extent.

It will be seen that the machine is exceedingly simple and inexpensive in construction, that it is adapted to be easily operated, and that it is capable of permitting a grinding and polishing wheel or device to rotate forwardly after its forward movement has ceased.

35 What is claimed is—

1. A machine of the class described, comprising a frame, carrying-wheels, a rotary device arranged to engage a floor or other supporting-surface, gearing connecting the rotary device with the carrying-wheels, and a

clutch connected with the gearing and adapted to permit the floor-engaging device to rotate while the carrying-wheels are stationary, substantially as and for the purpose described.

2. A machine of the class described comprising a supporting-frame, an axle journaled in suitable bearings at the back of the same, carrying-wheels fixed to the axle, the rear vertical shaft located above the axle, the vertical gear-wheel mounted on the axle, a horizontal pinion arranged at the lower end of the rear shaft and meshing with the vertical gear-wheel and having a clutch connection with the rear shaft, a vertical shaft arranged at the front of the frame and extending from the top to the bottom thereof and provided at its lower end with a grinding or polishing device, an intermediate vertical shaft located between the said shafts, and gearing arranged at the top of the frame and connecting the said shafts, substantially as described.

3. In a machine of the class described, the combination of the pinion provided with the grooves having inclined bottoms, the collar or member having sockets or recesses, balls arranged in the sockets or recesses and adapted to operate in the said grooves, means for connecting the pinion with the carrying-wheels, a shaft having the collar secured to it, and a grinding or polishing device connected by gearing with the shaft, substantially as described.

In testimony that I claim the foregoing as my own I have hereto affixed my signature in the presence of two witnesses.

SAMUEL A. BISHOP.
